US00D972006S

(12) **United States Design Patent** (10) Patent No.: **US D972,006 S**
Umezawa et al. (45) Date of Patent: **** Dec. 6, 2022**

(54) **X-Y PLOTTER FOR CUTTING**

(71) Applicant: **GRAPHTEC CORPORATION**,
 Kanagawa (JP)

(72) Inventors: **Takahisa Umezawa**, Kanagawa (JP);
Hiroshi Ohtsuka, Kanagawa (JP)

(73) Assignee: **GRAPHTEC CORPORATION**,
 Kanagawa (JP)

(**) Term: **15 Years**

(21) Appl. No.: **29/716,666**

(22) Filed: **Dec. 11, 2019**

(30) **Foreign Application Priority Data**

Jun. 14, 2019 (JP) 2019-013132

Primary Examiner — Lauren D McVey(74) *Attorney, Agent, or Firm* — Robert P. Michal, Esq.;
 Carter, DeLuca & Farrell LLP(57) **CLAIM**

The ornamental design for a X-Y plotter for cutting, as shown and described.

DESCRIPTION

FIG. 1 is a front view of a X-Y plotter for cutting showing our new design;

FIG. 2 is a rear view thereof;

FIG. 3 is a top plan view thereof;

FIG. 4 is a bottom plan view thereof;

FIG. 5 is a right side view thereof; and,

FIG. 6 is a left side view thereof.

The dot-dash broken lines depict the bounds of the claimed design while all evenly spaced broken lines are directed to environment. The broken lines form no part of the claimed design.
